UNITED STATES PATENT OFFICE.

JESSE S. KEPLER, OF DAYTON, OHIO, AND MILTON O. KEPLER, OF NEW YORK, N. Y.

DESIGN FOR A COMBINATION NUT BOWL AND CRACKER.

53,712.

Specification for Design.

Patented Aug. 19, 1919.

Application filed March 10, 1919. Serial No. 281,866. Term of patent 14 years.

To all whom it may concern:

Be it known that we, JESSE S. KEPLER and MILTON O. KEPLER, both citizens of the United States, residing at Dayton, in the county of Montgomery, State of Ohio, and New York, in the county of New York, State of New York, respectively, have invented a new, original, and ornamental Design for a Combination Nut Bowl and Cracker, of which the following is a specification, reference being had to the accompanying drawing, forming part thereof.

The figure is a side elevation of a combination nut bowl and cracker, showing our new design.

We claim:

The ornamental design for a combination nut bowl and cracker, substantially as shown.

In testimony whereof, we have hereunto set our hands this 27th day of February, A. D. 1919.

JESSE S. KEPLER.
MILTON O. KEPLER.

Witnesses:

WILLIAM A. SWANEY,
F. L. WALKER.
